DESIGN FOR A DOLL OR SIMILAR ARTICLE

Maurice Marossi, New York, N. Y.

Application March 3, 1945, Serial No. 118,247

Term of patent 3½ years

(Cl. D34—4)

To all whom it may concern:

Be it known that Maurice Marossi, citizen of Czechoslovakia and resident of New York city, in the county of New York and State of New York, has invented a new, original, and ornamental Design for a Doll or Similar Article, of which the following is a specification, reference being had to the accompanying drawing, forming part thereof, and in which,

Fig. 1 is a front view of the doll embodying my new design; and

Fig. 2 is a rear view thereof.

The essential features of my design reside in the portion disclosed in full lines.

I claim:

The ornamental design for a doll or similar article, substantially as shown and described.

MAURICE MAROSSI.
